AIR DISTRIBUTION SYSTEM FOR FLAME
TUBES OF GAS TURBINE ENGINES

Frank Morgan Owner and Francis Charles Ivor Merchant, Bristol, England, assignors to The Bristol Aeroplane Company Limited, Bristol, England, a British company

Application June 15, 1948, Serial No. 33,185

Claims priority, application Great Britain
June 17, 1947

7 Claims. (Cl. 60—39.37)

1

This invention concerns combustion apparatus for gas-turbine engines of the kind which comprises a pair of concentric generally cylindrical walls and the flame tubes extend lengthwise of the chamber within the annular space between the walls.

The present invention has for its object to provide an improved construction of combustion chamber of the kind referred to in which a uniform air distribution is obtained for the flame tubes.

According to this invention combustion apparatus for a gas turbine engine of the kind set forth is characterised in that there is provided for each flame tube a baffle which directs the air flowing through the annular chamber uniformly around the tube.

According to another feature of this invention each flame tube, which lies within the combustion chamber, is attached to the outer wall of the chamber by a single radial arm through which fuel is fed to the burner nozzle.

A practical application of the present invention will now be described, by way of example, with reference to the accompanying drawings whereof:

Figure 1 is a diagrammatic sectional elevation of a gas turbine engine in accordance with the invention.

Figure 2 is a sectional elevation in diagrammatic form of the combustion equipment of the engine of Figure 1.

Figure 3 is a section on the line 3—3 of Figure 1.

Figures 4, 5 and 6 are sectional elevations showing certain details of the combustion equipment.

Figure 7 is a partial view in the direction of arrow 7 of Figure 5.

Figure 8 is a view in the direction of the arrow 8 of Figure 7, and

Figure 9 is a partial section on the line 9—9 of Figure 5.

The engine (see Figure 1) comprises a compressor assembly 10, combustion equipment 11 and a turbine assembly 12. The combustion equipment 11 lies between the compressor assembly 10 and the turbine assembly 12 so that compressed air is delivered by assembly 10 to equipment 11 and, in turn, the combustion products are delivered to the turbine assembly 12.

The compressor assembly 10 comprises a low-pressure axial-flow compressor 13 and an axial-flow high-pressure compressor 14. The stator case 15 of compressor 13 is bolted to an annular

2

casing 16 which in turn is bolted to the stator casing 17 of the compressor 14. The annular casing conveys compressed air from the compressor 13 to the compressor 14. The compressor 14 delivers to a duct casing 18 which is bolted to the stator casing 17. The duct casing conveys air from the compressor assembly 10 to the combustion equipment 11.

The combustion equipment 11 generally comprises an annular combustion chamber, indicated at 19, within which there is a plurality of flame tubes 20 extending lengthwise of the chamber and spaced around it.

Air from the compressor assembly 10 is discharged through the annular duct 18 into the annular combustion chamber 19 and the products of combustion are discharged from said chamber into the turbine assembly 12 through an annular opening.

The combustion chamber 19 has an inner and an outer wall respectively indicated at 21, 22 (see also Figure 2). The walls 21, 22 are concentric and extend from the duct casing 18 to the guide vane assembly 23 of the turbine assembly 12.

The wall 22 is in three ring-like parts, namely an inlet part 24, a central part 25 and an outlet part 26. The part 24 is bolted to the casing 18 and the part 26 is bolted to the outer shroud ring 27 of the gas turbine. The central part 25 is bolted to the parts 24 and 26. The outer wall 22 thus connects the casing 18 to the turbine casing 27 and constitutes a stress-bearing member of the engine.

The central part 25 of wall 22 is removable to give access to the flame tubes 20—as hereinafter described.

To ensure that the air being supplied to the combustion chamber 19 is uniformly distributed around each flame tube there is provided for each such tube an inner and an outer baffle, respectively indicated at 28, 29 (see Figure 3).

The outer baffle 29, which is arcuate in cross-section lies over the upper part of the outer surface of each flame tube 20 to define therewith an arcuate space 30 extending throughout the length of the tube. The long edges 31 of adjacent baffles 29 lie near to each other so that a complete assembly is built up around the flame tubes.

The inner baffles 28 are formed in a cylindrical element having a plurality of lengthwise extending troughs 32 within each of which the bottom part of a flame tube lies. In this way adjacent long edges of the inner baffles meet together to

form a continuous assembly around the long axis of the combustion chamber. The wall of each trough 32 goes part-way up its flame tube and defines with it an arcuate space 33 extending over the length of the tube and along which air from the compressor passes.

The baffles 28, 29 prevent air from coming into contact with walls 21, 22. Due to the high temperatures of operation in the combustion equipment 11 it is necessary to cool the walls 21, 22. To this end the baffles 28, 29 are respectively spaced from the inner and outer walls 21, 22 as at 34, 35 and cold air is passed through bleed openings in the baffles to travel lengthwise through the spaces 34, 35 over the walls 21, 22. This construction also avoids pressure differences on the baffles.

The details of this cooling arrangement are more clearly shown in Figures 4, 5 and 6 to which reference will now be had. As shown in Figure 4 the inner wall 21 is welded to a flanged ring 36 which is bolted to the casing 18. The baffle 28 is also supported by ring 36, the end of the baffle which is so supported being slit lengthwise at a plurality of points around it to form resilient fingers 37. The latter engage the wall 21 and support the baffle therefrom. The fingers 37 lie in a stepped part of the wall 21 and, in order to provide a smooth entry for the air entering the combustion chamber 19, the baffle 28 carries a plate 38. This plate is spaced by a small amount, as at 39, from the casing 18 and ring 36 so that air may pass from the casing 18 to behind the plate 38 and thence between the fingers 37 into the space 34.

The inner baffle 28 is formed in two ring-like parts (see Figures 2 and 5) which are spaced apart, at 40, so that air travelling along the space 33 passes through the opening 40 into space 34 at the rear of the baffle 28. This air, which is under pressure, passes towards the turbine assembly 12.

Each outer baffle 29 is formed in three parts corresponding to the three parts 24, 25 and 26 of the wall 22. That part 41 of the baffle 29 which corresponds to the part 24 of the wall 22 is attached to and carried by said part of the wall. As indicated above, the part 41 is spaced from the part 24. A boss 42 (Figure 4) is bolted to the wall part 24 and passes through the part 41 of baffle 29. The purpose of the boss 42 will be made clear later. An opening 43 is formed between the baffle part 41 and the boss 42 so that air may leak to behind the part 41 to cool the wall part 24. The central part 44 of each baffle 29 (which corresponds to the wall part 25) is attached to said part 25 by a single bolt 45 the purpose of which will shortly be described. The third part 46 of baffle 29 is associated with part 26 of wall 22 and is supported therefrom by two rows of circumferentially spaced members 47. The members 41, 46 are respectively forked as at 48, 49 each to receive an edge of the central part 44 of each baffle 29.

For inspection and maintenance purposes the bolts 45 are removed from the central part 25 of the wall 22 and thereafter the said part is unbolted from parts 24 and 26 said slid lengthwise off the engine. The part 44 of any one, or more, of the baffles 29 may then be slid lengthwise (towards the right in Figure 6) so that its left hand end leaves the fork 48 whereupon it may be raised outwardly and entirely removed. In this way access may be had to the flame tubes 20.

For assembly the process is reversed. After the

central part 25 of the wall 22 is bolted in position to parts 24, 26 the bolt 45 is screwed home to hold the central part 44 of the baffle 29 against the part 25 of the wall 22 and spaced therefrom.

5 The part 44 of each baffle 29 has one or more holes 50 (Figure 6) whereby cooling air additional to that leaking through the opening 43 may pass to the space 35 for cooling purposes as above described.

10 The flame tube 20 is formed in four portions 51, 52, 53 and 54 (see Figures 1 and 2).

The portion 51 (Figure 4) carries the fuel nozzle 55 and is constituted by a thin-walled casting which is integrally formed with the boss 42.

15 The latter is generally radially disposed of the portion 51 and is bolted to the part 24 of the wall 22. The boss 42 is formed with a gland 56 through which a fuel pipe 57 passes, from the outside combustion chamber, to the nozzle 55. The 20 boss 42 is of streamlined formation in the direction of flow of air over the flame tube. A plate 58 prevents access to the interior of the boss 42. The latter constitutes the sole point of attachment of the flame tube 20 to the combustion 25 chamber—the discharge end of the flame tube is, however, supported as hereinafter described.

The casting 51 is formed with a snout 59 having an opening 60 through which primary air passes to around the fuel nozzle 55 in known manner. A swirling motion is imparted to the 30 primary air by a series of vanes 61 which lie around the nozzle 55 and constitute a part of a spider which supports the nozzle. The vanes 61 are integrally formed during casting.

35 The portion 52 of the flame tube 29 (Figure 6) is constituted by a circular, thin sheet-metal member which is suitably attached to the casting 51 and is formed with openings 62 (Figure 2) through which secondary air passes. The portion 53 is of similar construction and is attached to the portion 52 as by welding. This portion is also formed with holes whereby more of the secondary air may enter the flame tube.

The portion 53 is spigoted into the portion 54 (Figure 5) and has its edge crimped at 63 so that 45 air passages are formed between these two parts. The spigot joint provides a support for the portions 51, 52, 53 of the flame tube whilst allowing for lengthwise movements due to expansions and contractions of the flame tube.

The portion 54 is constituted as a breeches piece. The breeches piece has, for each flame tube, a circular entry to receive the crimped end of portion 53 of the tube and a rectangular discharge end which gives into the turbine assembly 12. At their discharge ends the adjacent sides of adjacent breeches pieces are cut away at 64 (Figure 5) and welded together along their abutting edges thereby to form a continuous annular exit 65. The breeches pieces 54 are each supported by a plurality of circumferentially spaced top-hat members 66 which are carried by the inner baffle 28.

The mouth of the annular exit 65 is a short distance from the nozzle guide-vane assembly as at 67, 68. The cooling air passing along the space 35 between the baffle 29 and the wall 22 is discharged through the opening 68 into the stream of combustion products at the nozzle box of the 70 turbine. Similarly, the cooling air flowing along the space 34 between the wall 21 and the baffle 28 is discharged through the opening 67 into the stream of combustion products. As this air is under pressure it prevents leakage of the combustion products through the openings 67, 68 so

that an effective seal is formed at the nozzle box. A metered quantity of air from space 34 may pass through the diaphragm 69 (Figure 2) and be directed into the turbine for cooling the discs thereof.

Referring again to Figure 6: a torch or plug igniter 70 is provided to start the combustion operation, the igniter being provided in known manner, and extending through the wall 22 to within one of the flame tubes 20. In previous constructions where there has been provided a plurality of separate combustion chambers it has been usual to provide two such firing points and to interconnect the separate combustion chambers for even flame distribution and equalization of pressure. In the present arrangement a simplified construction is permitted. Thus, the interconnections may comprise a stub pipe projecting from the near sides of adjacent flame tubes, the pipes being open-ended with the adjacent ends spaced apart by a small amount.

The outer wall 22 of the combustion chamber 19 is adapted to constitute part of a stress-bearing member the other elements of which are the casings 13, 14 and 18, the conduit 16 and the shroud ring 27. The engine is thus enveloped throughout its length in a tubular load-carrying member. With this arrangement the outer wall 22 will transmit the engine loads from the turbine assembly 12 to the compressor assembly 10 and vice versa. When, however, the part 25 of the wall 22 is removed these loads must be so transmitted through another structure.

To this end, the inner wall 21 is bolted to the casing 18, as above described, and is also welded to a ring carried by diaphragm 69 (Figure 2). The casing 18 has also bolted to it a diaphragm 71 and the diaphragms 69, 71 carry roller bearings 72, 73 whereby the shaft 74 of the rotor disc 75 of assembly 12 is supported (Figure 1).

The diaphragm 69 engages pistonwise on a ring 76 of the guide-vane assembly 23 (Figure 5) a piston ring seal 77 being provided between the two.

The guide-vane assembly 23 comprises a plurality of guide vanes 78 integrally formed with an inner and outer carrier 79 and 80 respectively. As shown in Figure 7, a group of such guide vanes 78 together with the carriers 79 and 80 constitute a sector member. The latter are mounted end-to-end around the assembly to form a complete ring of blades. The sector members are supported by the inner and outer rings of the guide-vane assembly 23—so that each is free to expand and contract in an outward radial direction or in a circumferential direction relatively to each other and relatively to the guide-vane rings. To this end, firstly the carrier 79 of each sector member is held to the inner ring of the assembly 23, being clamped between two annular plates 81, 82 (Figure 5) which constitute said inner ring. Secondly, the outer carrier 80 is radially spaced from the outer ring 83 of the guide-vane assembly (see Figure 9) and, thirdly, adjacent sector members are spaced apart circumferentially as at 84, Figure 8. Thus, each sector member (with the exceptions about to be mentioned) is supported solely by the inner ring of the guide-vane assembly and projects radially outwardly therefrom in spaced relationship to the adjacent members and the outer ring 83 of the assembly. The carrier 80 of each sector member is slotted as at 85 to receive the head 86 of a pin 87 the shank of which enters a hole in the ring 83.

It is arranged (see Figure 9) that at two dia-

metrically opposite points of the assembly 23, and in a horizontal plane, a bolt 88 is screw-threaded into the outer ring 83 so that its end face 89 enters and accurately fits a radial hole 90 at the bottom of the slot 85. (Figures 7 and 8 show the sector member which is modified by having the hole 90 formed in it to receive the bolt 88.) When the bolt 88 is screwed home the ring 83 is rigidly connected with the ring 81, 82 through the associated sector member.

When the part 25 of the wall 22 is removed for inspection, or other purposes, the engine will be at rest so that the loads imposed on the engine shell are due primarily to the weight of the installation. With removal of the wall 25 the loads on the turbine due to its weight are transmitted to the compressor and vice versa through, firstly, the ring 83, secondly the bolts 88, thirdly, the associated sector members in the horizontal plane of the engine, fourthly, the inner ring 81, 82 and, finally, the diaphragm 69 and the inner wall 21 of the combustion apparatus.

Of course, it will be understood that with the arrangement described whilst the part 25 of wall 22 is in position the loads are transmitted partly through the outer and partly through the inner walls 22, 21 respectively of the combustion chamber.

We claim:

1. In combustion apparatus for a gas turbine engine of the kind set forth having inner and outer concentric walls of which the outer wall is removable, flame tubes between said inner and outer walls, an inner baffle member having a separate baffle portion for each flame tube, an outer separate baffle for each flame tube, said inner and outer baffles being spaced from each tube and following the general outline of the flame tube at a substantially constant distance therefrom and means for independently attaching each outer baffle to the outer wall so that, on removal of said outer wall, each outer baffle is separately removable to give access to its flame tube.

2. Combustion apparatus according to claim 1 in which there are holes through each baffle to allow part of the air passing over the flame tube to enter and pass along a space between the baffle and the wall which carries the baffle.

3. Combustion apparatus as claimed in claim 1 in which the outer wall and outer baffle are each in three parts lying end to end in the lengthwise direction of the flame tubes and the central part of the wall and baffle is removable to give access to the flame tubes.

4. Combustion apparatus as claimed in claim 3 in which the side parts of an outer baffle are forked to receive the ends of the central part thereof as a sliding fit which permits one end of the central part to be removed prior to the withdrawal of said part.

5. Combustion apparatus as claimed in claim 4 wherein each flame tube is attached to a non-removable side part of the outer wall of the combustion chamber solely by a single radial arm which in extending from said wall to the flame tube passes through a non-removable side part of the outer baffle, the fuel being fed to the burner nozzle through said arm.

6. Combustion apparatus according to claim 5 in which the support arm and the associated end of the flame tube are integrally formed as a casting, said arm being removably attached to a lateral part of the outer wall.

7. Combustion apparatus as claimed in claim 6

wherein the burner nozzle is mounted within a group of primary-air swirl vanes which are integrally cast with the flame tube and its support.
